(74) *Attorney, Agent, or Firm* — ArentFox Schiff LLP

(57) **CLAIM**

The ornamental design for a cassette, as shown and described.

DESCRIPTION

FIG. 1 is a front perspective view of a cassette;

FIG. 2 is a front view thereof;

FIG. 3 is a right side view thereof;

FIG. 4 is a left side view thereof;

FIG. 5 is a top plan view thereof; and,

FIG. 6 is a bottom plan view thereof.

The broken lines show portions that form no part of the claimed design.

The back of the cassette forms no part of the claimed design.
